UNITED STATES PATENT OFFICE.

BOLESLAV DLOUHÝ, OF NEW YORK, N. Y.

SMOKELESS MUFFLER.

965,090.

Specification of Letters Patent. Patented July 19, 1910.

Application filed April 5, 1910. Serial No. 553,490.

To all whom it may concern:

Be it known that I, BOLESLAV DLOUHÝ, a subject of the Emperor of Austria-Hungary, and a resident of the city of New York, 5 borough of Manhattan, in the county and State of New York, have invented a new and Improved Smokeless Muffler, of which the following is a full, clear, and exact description.

10 An object of the invention is to provide a new and improved muffler, arranged to deaden the noise of the exhaust gases and to deprive the same of smoke.

For the purpose mentioned, use is made 15 of a casing having a zigzag passage for the exhaust gases from the engine, and liquid jets for the gases, to condense the same and deprive the gases of smoke.

A practical embodiment of the invention 20 is represented in the accompanying drawings forming a part of this specification, in which similar characters of reference indicate corresponding parts in both views.

Figure 1 is a cross section of the improved 25 smokeless muffler as applied, and Fig. 2 is a longitudinal section of the muffler.

The casing A, is preferably made cylindrical, and is connected near one end with the exhaust pipe B of an internal combustion 30 engine, and within the casing A are arranged transverse baffle plates C, provided with apertures D, D' located alternately at the bottom and top of successive plates C, to provide a zigzag passage through the casing A, for the exhaust gases to travel 35 through from the inlet at the pipe B to the outlet E at the other end of the casing A. By the use of the baffle plates C, the noise of the exhaust gases is gradually deadened 40 and the baffle plates C form within the casing A separate compartments, each of which is provided at the top with a spraying nozzle F, connected by a branch pipe G' with a water supply pipe G, connected with a 45 pump H, having its suction pipe I extending into a reservoir J, connected by a pipe K with the bottom of the muffler casing A. The pump H may be the pump usually employed for circulating water through the 50 cylinder jacket to keep the engine cylinder cooled.

When the engine is in use and the pump H is running, then the exhaust gases from the engine are passed through the zigzag 55 passage in the casing A, and water is pumped by the pump H into the nozzles F

by way of the pipe G. The water passing into the nozzles F is sprayed by the latter onto the exhaust gases passing through the casing A, so that the gases are deprived of the smoke, and the water flows along the bottom of the casing into the pipe K, to return to the reservoir J, from which the water is drawn by the pump H. Any oil, 60 grease or other extraneous matter precipitated from the exhaust gases by the sprayed water in the casing A, is carried along by the water to the reservoir J, from which the extraneous matter may be drained periodically by opening a drain cock L. The baffle 65 plates C are provided at the bottom with apertures D² for the passage of the water to the pipe K.

From the foregoing, it will be seen that the force of the exhaust gases is broken during the travel of the gases through the zigzag passage in the casing A, and the smoke and vapors are condensed by the sprays of water, so that the gases finally escaping at the outlet E are practically noiseless and 80 free of obnoxious smoke and smell.

The muffler described is exceedingly serviceable for use on automobiles, motor boats and other vehicles using gasoline, or other internal combustion engines.

Having thus described my invention, I claim as new and desire to secure by Letters Patent:

1. A smokeless muffler, comprising a casing having an inlet and an outlet for the exhaust gases, baffle plates in the casing to provide a zigzag passage for the gases while passing from the inlet to the outlet, and nozzles located between adjacent baffle plates and connected with a liquid supply 95 for spraying a liquid onto the gases during their passage through the casing.

2. A smokeless muffler comprising a casing having an inlet and an outlet for the exhaust gases from an engine, baffle plates in the said casing to provide a zigzag passage for the exhaust gases, nozzles in the top of the casing intermediate adjacent baffle plates, a pump connected with the said nozzles, and a reservoir connected with the said casing to receive the water from the latter, the suction pipe of the said pump extending into the reservoir.

3. A smokeless muffler, comprising a casing having an inlet and an outlet for the exhaust gases from an engine, baffle plates in the said casing to provide a zigzag pas-

- sage for the exhaust gases, nozzles in the top of the casing intermediate adjacent baffle plates, a pump connected with the said nozzles, a reservoir connected with the said casing to receive the water from the latter, the suction pipe of the said pump extending into the reservoir, and draining means on the reservoir for draining off oil and other extraneous matter.
- 10 4. A smokeless muffler, comprising a casing, an inlet pipe for exhaust gases connected with one end of said casing, and an outlet at the other end, a series of transverse baffle plates within the casing and forming with the casing separate compartments, each baffle plate being provided with apertures located alternately at the bottom and top of successive plates, a spraying nozzle at the top of each compartment, and a water supply pipe connected with said nozzles.
- 15 5. A smokeless muffler, comprising a casing through which the exhaust gases pass, spraying devices in the casing, a reservoir connected with the casing to receive the water from the latter, and means for forcing the water from the reservoir to said spraying devices.
- 20 6. A smokeless muffler, comprising a casing having an inlet and an outlet for the

exhaust gases, means for providing a zig-zag passage for the gases while passing from the inlet to the outlet, means for spraying a liquid onto the gases during the passage through the casing, a reservoir connected with the casing to receive the water from the latter, and a pump connected with the reservoir.

7. A smokeless muffler, comprising a casing having an inlet and an outlet for the exhaust gases, baffle plates in the said casing to provide a zig-zag passage for the exhaust gases, nozzles in the top of the casing, a reservoir, a pipe leading from the bottom of the casing to said reservoir, the said baffle plates being provided at the bottom with apertures for the passage of the water to said pipe, a water supply pipe connected with the nozzles, and a pump with which said water supply pipe is connected, the suction pipe of said pump extending into said reservoir.

In testimony whereof I have signed my name to this specification in the presence of two subscribing witnesses.

BOLESLAV DLLOUHY.
